TOP ENDGATE

Charles R. Adams, Donavon, Saskatchewan,
Canada

Application September 18, 1946, Serial No. 697,771

6 Claims. (Cl. 296—51)

1

My invention relates to improvements in top end-gates for wagon or truck boxes for use in combination with the bottom end-gate illustrated and described in my continuation-in-part application Serial No. 623,564, an object of the invention being to provide an assembly of the character herewithin described which will eliminate the usual channels on either side of the rear end of the box, and which necessitate the raising of the gate bodily in the removal thereof from said channels, which bodily lifting is strenuous and fatiguing inasmuch as the end-gate in question is necessarily of substantial weight, to which must be added the liability to bind against one channel or the other should it be skewed slightly in the act of lifting.

A further object of the present invention is to eliminate the usual cross-rods and tail nuts for preventing spreading of the side-walls under load, and, by such elimination, to provide a more positive, sealing union between the end-gate and the side-walls.

A further object of the present invention is to provide an end-gate which also fulfills the function of the aforesaid cross-rod within itself, and which, thereby eliminates the necessity for any subsequent cross-rod removal when for example it is desired to load oil-barrels after hauling loose grain, gravel or the like.

A further object is to provide a device of the character herewithin described which is conspicuously simple and of rugged construction, and which, when in situ will be rigid and free from rattling.

With the foregoing objects in view, and such other objects and advantages as will become apparent to those skilled in the art to which this invention relates as this specification proceeds, my invention consists essentially in the arrangement and construction of parts all as hereinafter more particularly described, reference being had to the accompanying drawings, in which:

Figure 1 is a compressed, and partly fragmented representation of my top end-gate in combination with the bottom end-gate of my continuation-in-part application Serial No. 623,564.

Figure 2 is a plan view of the assembly of Figure 1.

Figure 3 is a section on the line 3—3 of Figure 2.

Figure 4 is a section on the line 4—4 of Figure 1.

Figure 5 is an enlarged plan detail of the right-hand end structure of Figure 2.

2

In the drawings like characters of reference indicate corresponding parts in the different figures.

According to my observations, most top-end gates are constructed upon the principle of the conventional wagon-box type top end-gate which consists of a rectangular gate panel usually of wood suitably reinforced and designed to drop into a pair of channels at the rear ends of the side walls of the box. Cross-rods or tightener-rods span the rear corners of the side walls, apertures being provided in the side walls for this purpose. After the gate has been dropped into the channels, a tail-nut is tightened on the screw-threaded end of the rod against the side wall corner so that the pair of channels is cramped against the vertical side edges of the gate panel.

The disadvantages of the above arrangement reside first in the fact that if the thickness of the gate-panel is substantially less than the space between the flanges of the channels, when the box is loaded with loose material such as grain, such load forces the gate tightly against the rear or outer flanges of the pair of channels so that the material enters between the front gate panel surface and the interior or front flanges where it binds thus rendering the removal of the gate panel very difficult.

Secondly, if the gate panel is a snug fit within a pair of channels, only a small amount of moisture will suffice to swell the wood and again cause undesirable binding without first spreading the side walls by slackening the aforesaid tail-nut.

My invention accordingly consists of a top end-gate panel collectively designated 1, rabbeted into the upper horizontal edge of which is an elongated tie-member in the form of an angle bar 2 having apertures 3 extending through the ends of the vertical flange 4 thereof as well as through the wood in line therewith to receive the studs 5.

Welded to the rear edges of a metal strip 6 secured against the inner end surfaces of the side walls 7 and to the deck 8 of the body 9 (which strip is designated 39 in my continuation-in-part Serial No. 623,564) are vertical flanges 10, the upper ends whereof are provided with ear-pieces 11 having apertures therein through which the aforesaid studs 5 extend, being preferably welded in such position. It will thus be observed that my gate panel 1 is positioned in front of the pair of flanges 10 which, as will also clearly be observed, are in transverse coplanar relationship.

Positioned parallel with the side edges of gate

panel 1, and somewhat inset with respect to such side edges are angle bars 12 which serve to reinforce my gate panel, and are provided approximately intermediately of the lengths thereof with the pieces of metal 13 (reinforced if desired with a web 14) constituting diagonal thrust surfaces against a crank-handled bolt or shank 15 may be advanced.

The crank handles 15 project upon the exterior surfaces of the side walls 7 and extend through apertures provided therefor in the side-wall supporting stakes 16. The inner ends of the aforesaid bolts are externally screwthreaded as at 17, and move upon rotation of the handle portion, in the internally screw-threaded bushings 18 welded against the outer surfaces of the vertical portions of the strip 6.

From the foregoing it will clearly be apparent that when the cranks 15 are rotated in one direction, the inner ends thereof will ride against the thrust surfaces 13 so binding my gate panel sealingly against the flanges 10. At the same time the side walls 7 are sustained against spreading by the studs 5 in combination with the tie-member 2, and simply upon rotation of the cranks 15 in the opposite direction, my gate panel may be released and laid upon the deck 8.

It will be noted that I also provide an angle bar 19 upon the lower horizontal edge of my gate panel 1, the same projecting rearwardly to the extent of the thickness of the flanges 10 so that a horizontal seal is provided to close the elongated horizontal aperture or slot which would otherwise exist at 20 between the exterior surface of my gate panel 1 and my bottom end-gate 28. It is also to be understood that flanges 10 terminate at the lower ends thereof approximately coincident with the aforesaid lower horizontal edge of panel 1 since to extend them downwardly further than this would be unnecessary.

For purposes of orientation in connection with the structure of my continuation-in-part application Serial No. 623,564 I have, in the accompanying drawings employed corresponding numerals in respect of parts shown in this and the above identified application, and since various modifications can be made in my invention as hereinabove described and many apparently widely different embodiments of same made within the spirit and scope of the claims without departing from such spirit and scope, it is intended that all matter contained in the accompanying specification shall be interpreted as illustrative only and not in a limiting sense.

What I claim as my invention is:

1. A top end-gate assembly for wagon or truck boxes comprising in combination a rectangular gate-panel and structure supporting same, said supporting structure embodying a pair of vertical opposing flanges on the rear ends of the wagon or truck box sidewalls extending normally towards each other therefrom, an elongated tie-member secured to said panel parallel with the top edge thereof and at least adjacent thereto, studs extending through the ends of said tie-member and the upper ends of said flanges for suspending said panel in situ and to counteract the spreading of said truck or wagon box side walls under load, and means upon said side walls adjacent said flanges for progressively tightening the panel edges adjacent thereto against said flanges.

2. A top end-gate assembly for wagon or truck boxes comprising in combination a rectangular gate-panel and structure supporting same, said

supporting structure embodying a pair of co-planar vertical opposing flanges on the rear ends of the wagon or truck box side-walls extending normally towards each other therefrom, an elongated tie-member secured to said panel parallel with the top edge thereof and at least adjacent thereto, studs extending through the ends of said tie-member and the upper ends of said flanges for suspending said panel in situ and to counteract

10 the spreading of said truck or wagon box side walls under load, and means for progressively tightening at least one edge of said panel against that one of said opposing flanges which is adjacent thereto.

15 3. A top end-gate assembly for wagon or truck boxes comprising in combination a rectangular gate-panel and structure supporting same, said supporting structure embodying a pair of vertical opposing flanges on the rear ends of the wagon or truck box side-walls extending normally towards each other therefrom, an elongated tie-member in the form of an angle-bar secured to said panel parallel with the top edge thereof, and at least adjacent thereto, studs extending through

20 the ends of said angle-bar and the upper ends of said flanges for suspending said panel in situ and to counteract the spreading of said truck or wagon box side walls under load, and means upon said side walls adjacent said flanges for progressively tightening the panel edges adjacent thereto against said flanges.

25 4. A top end-gate assembly for wagon or truck boxes comprising in combination a rectangular gate-panel and structure supporting same, said supporting structure embodying a pair of co-planar vertical opposing flanges on the rear ends of the wagon or truck box side-walls extending normally towards each other therefrom, said panel when in situ being in front of said flanges, and

30 5. A top end-gate assembly for wagon or truck boxes comprising in combination a rectangular gate-panel and structure supporting same, said supporting structure embodying a pair of co-planar vertical opposing flanges on the rear ends of the wagon or truck box side-walls extending normally towards each other therefrom, said panel when in situ being in front of said flanges, and

35 6. A top end-gate assembly for wagon or truck boxes comprising in combination a rectangular gate-panel and structure supporting same, said supporting structure embodying a pair of co-planar vertical opposing flanges on the rear ends of the wagon or truck box side-walls extending normally towards each other therefrom, said panel when in situ being in front of said flanges, and

40 7. A top end-gate assembly for wagon or truck boxes comprising in combination a rectangular gate-panel and structure supporting same, said supporting structure embodying a pair of co-planar vertical opposing flanges on the rear ends of the wagon or truck box side-walls extending normally towards each other therefrom, said panel when in situ being in front of said flanges, and

45 8. A top end-gate assembly for wagon or truck boxes comprising in combination a rectangular gate-panel and structure supporting same, said supporting structure embodying a pair of co-planar vertical opposing flanges on the rear ends of the wagon or truck box side-walls extending normally towards each other therefrom, said panel when in situ being in front of said flanges, and

50 9. A top end-gate assembly for wagon or truck boxes comprising in combination a rectangular gate-panel and structure supporting same, said supporting structure embodying a pair of co-planar vertical opposing flanges on the rear ends of the wagon or truck box side-walls extending normally towards each other therefrom, said panel when in situ being in front of said flanges, and

55 10. A top end-gate assembly for wagon or truck boxes comprising in combination a rectangular gate-panel and structure supporting same, said supporting structure embodying a pair of co-planar vertical opposing flanges on the rear ends of the wagon or truck box side-walls extending normally towards each other therefrom, said panel when in situ being in front of said flanges, and

60 11. A top end-gate assembly for wagon or truck boxes comprising in combination a rectangular gate-panel and structure supporting same, said supporting structure embodying a pair of co-planar vertical opposing flanges on the rear ends of the wagon or truck box side-walls extending normally towards each other therefrom, said panel when in situ being in front of said flanges, and

65 12. A top end-gate assembly for wagon or truck boxes comprising in combination a rectangular gate-panel and structure supporting same, said supporting structure embodying a pair of co-planar vertical opposing flanges on the rear ends of the wagon or truck box side-walls extending normally towards each other therefrom, said panel when in situ being in front of said flanges, and

70 13. A top end-gate assembly for wagon or truck boxes comprising in combination a rectangular gate-panel and structure supporting same, said supporting structure embodying a pair of co-planar vertical opposing flanges on the rear ends of the wagon or truck box side-walls extending normally towards each other therefrom, said panel when in situ being in front of said flanges, and

75 14. A top end-gate assembly for wagon or truck boxes comprising in combination a rectangular gate-panel and structure supporting same, said supporting structure embodying a pair of co-planar vertical opposing flanges on the rear ends of the wagon or truck box side-walls extending normally towards each other therefrom, said panel when in situ being in front of said flanges, and

walls, extending normally towards each other therefrom, an elongated tie-member secured to said panel parallel with the top edge thereof at least adjacent thereto, studs extending through the ends of said tie-member and the upper ends of said flanges for suspending said panel in situ and to counteract the spreading of said truck or wagon box side-walls under load, and means upon at least one of said side walls adjacent the flange thereon for tightening the adjacent panel-edge thereagainst, consisting of an internally threaded bushing on said side-wall a screw-threaded shank extending therethrough, and an element secured to said gate-panel having

6
a diagonal thrust surface against which said shank bears to seal said panel-edge against said flange.
